[57] CLAIM

The ornamental design for a combine right side panel unit, as shown and described.

DESCRIPTION

FIG. 1 is a side view of a combine right side panel unit showing our new design, the broken lines showing of the vehicle and ground line being for illustrative purposes only, and forms no part of the claimed design.

FIG. 2 is an enlarged top view of the combine right side panel unit design of FIG. 1.

FIG. 3 is a side view of the combine right side panel unit of FIG. 2.

FIG. 4 is a bottom view of the combine right side panel unit of FIG. 2.

FIG. 5 is a front view of the combine right side panel unit of FIG. 2; and,

FIG. 6 is a rear view of the combine right side panel unit of FIG. 2.
